UNITED STATES PATENT OFFICE.

DOLPH MAUPIN, OF CARROLLTON, MISSOURI.

ACETYLENE-GAS GENERATOR.

Application filed January 10, 1921. Serial No. 436,815.

To all whom it may concern:

Be it known that I, DOLPH MAUPIN, a citizen of the United States, and resident of Carrollton, county of Carroll and State of Missouri, have invented a certain new and useful Improvement in Acetylene-Gas Generators, of which the following is a complete specification.

This invention relates to acetylene gas generators, and more especially to that class of generators to be arranged in a pit outside of a building, by preference, for supplying gas for illumination purposes, and my object is to produce a generator which will effect the automatic generation of gas whenever the supply of the same is substantially exhausted, until the entire supply of carbide is exhausted. A further object is to provide a generator of this character equipped with a reserve supply of carbide, and means whereby such reserve supply can be manually discharged into the magazine to continue the automatic generation of gas for a further predetermined length of time.

A still further object is to produce an acetylene gas generator of simple, strong, durable and inexpensive construction.

With these objects in view the invention consists in certain novel and useful features of construction and combinations of parts as hereinafter described and claimed; and in order that it may be fully understood, reference is to be had to the accompanying drawing, in which:

Figure 1, is a view partly in elevation and partly in central vertical section, of a gas generator embodying the invention.

Figure 2, is a vertical section on the line II-II of Figure 1.

Figure 3, is an enlarged plan view of a part of the carbide magazine or holder to illustrate more clearly the construction of the reserve carbide container.

Figure 4, is a sectional perspective view to disclose more clearly certain details of the construction of the reserve carbide container.

In the said drawing, a tank to be almost wholly buried in the ground, comprises the lower portion or water container 1, the upper portion 2 of reduced diameter, and a removable cover 2^a; the portion 2 forming in conjunction with an inner wall 3 flanged outward at its lower end, a circular liquid seal chamber 4. The wall 3 is provided

with an internal bead 5 to constitute a support for a carbide magazine 6, the latter having an external bead 7 resting on bead 5. The lower part of the magazine tapers downwardly and has a discharge opening at its lower end or apex, and near its upper end, said magazine is provided with a cross bar 8 as a support for a vertical tube 9 disposed vertically over the apex of the magazine. The tube terminates at its lower end in an outwardly-flaring or conical skirt 10 disposed a short distance above the discharge opening of the magazine to guard against a too liberal discharge of carbide into the tank when the controlling valve of the magazine is opened.

The controlling valve is preferably in the form of a flat plate or disk 11 secured to the lower end of a vertical rod 12, extending up through tube 9 and terminating in a plane above the upper end of the same, and to hold the valve elevated and normally closing the orifice at the apex of the tapering or inverted conical portion of the magazine, spiral spring 13 fits around rod 12 within tube 9, and bears at its lower end against a cross piece 14 at the lower end of the tube, and at its upper end against a collar 15 secured on said rod. When unresisted, the spring will close the valve against the magazine and thus prevent carbide escaping through said opening.

The magazine is provided with a removable cover 16, held in place by frictional grip or otherwise. Through the top of the cover the tube 9 and rod 12 project, so that when the gas bell or holder 17 descends a sufficient distance, as hereinafter explained, it will press said rod downward with sufficient force to overcome the resistance of spring 13 and lower or unseat said valve 11 to effect a discharge of carbide into the water in the generator tank, this action being indicated in Figure 1. The wall of the bell or holder depends into the liquid-seal chamber, so that gas entering the bell or holder, through the cover 16 and a slot hereinafter mentioned, shall be excluded from the chamber or portion 2 of the generator above the liquid-seal exterior to the gas bell. For convenience in venting air from the bell when gas is first generated in the tank, a pet-cock 17^a is provided at the top of the bell, and for handling the bell or holder, it is provided with a pair of handles, as at 18. Arranged within the magazine is a re-

serve carbide holder 19, the wall of the magazine constituting one wall of said holder by preference. The bottom 20 of said holder slopes downwardly and inwardly 5 and is provided with a discharge-opening 21, normally closed by a suitable hinged sub-bottom or valve 22, which is provided with an outwardly projecting lug 23. Arranged within the reserve carbide holder 10 and against and pivoted to the inner wall thereof, is a catch 24, provided at its lower end with a hook 25 to engage under the lug 23 of the valve 22 and hold the latter normally closed to guard against the escape 15 of carbide from said holder. The pivoted catch 24 extends upward through a slot 26 through which gas may pass as above referred to in the free edge of a hinged cap 27 mounted on the cover of the magazine 20 to close the opening 28 therein except for said slot 26. The reserve charge of carbide can be easily deposited in holder 19, by opening cap 27, without removing the magazine cover. The catch 24 terminates at its 25 upper end in a laterally projecting arm 29 standing in the path of a lug 30 depending from the inner side of the top of the bell or holder 17, so that when the latter is in fully depressed position, and grasped and manually turned, the pressure of the lug 30 on the arm 29 shall operate and thereby trip the catch from under the lug 23 of valve 22 and permit said valve under the weight of the carbide to drop to permit the carbide 30 to pass into the magazine. Underlying the reserve holder is a retarder 31 in the form of an inverted V-shaped arm projecting from the wall of the magazine, this arm retarding but not completely arresting the 35 feed of the carbide from the reserve holder into the magazine, to provide sufficient time for a quantity of carbide to enter the water and result in the production of gas to cause the bell to rise and close the valve 11 prior 40 to the complete evacuation of the reserve holder into the magazine. The retarder thus permits of the employment of a sufficient reserve supply of carbide to charge the bell with gas more than once. The auxiliary 45 charge of carbide as customary, is for use when the supply in the magazine becomes exhausted as indicated by the lights getting low or becoming extinguished. When this occurs the bell is fully depressed and, the operator can remove the top or cover 2^a, and turn the bell or holder by handles 18 until lug 30 performs the function as herein before explained.

This generator has the same general mode 60 of operation as old generators of this general type, that is to say when a charge of carbide drops into the water of portion 1, gas is generated under sufficient pressure to raise the bell, and as this occurs the spring 65 13 reseats the valve and cuts off the dis-

charge of carbide. As the gas in the bell is used, the bell descends gradually and eventually imposes its weight on the stem 12 of the valve and unseats the same and thus effects a repetition of the generation 70 operation and the reelevation of the bell, these actions being repeated until the entire supply of carbide in the magazine is exhausted.

With a flat valve engaging the relatively 75 sharp lower edge of the magazine at the margin of the discharge opening, any interposed lumps of carbide will be crushed or broken to permit the valve to be properly seated. The magazine is provided with 80 a ring 6^a for protecting the carbide adjacent the valve, from excessive moisture.

The gas is drawn off from the chamber of portion 1 above the water therein through a pipe 32 equipped with a filter 33 of any 85 suitable type, located within the tank or exterior thereto as shown, and when it is desired to have access to the interior of the generator, the gas can be cut off in said pipe by the operation of the customary valve 34 90 mounted in the tube 35 adjacent the generator or located at any other convenient point. The valve is accessible through a housing tube 36 provided with a removable cap 37.

When the magazine is recharged, a reserve 95 charge is also placed in the reserve carbide chamber and the valve 22 of the same is closed and secured in such position by the adjustment of the catch 24 to the position shown most clearly in Figure 4.

From the above description it will be apparent that I have produced an acetylene generator embodying the features of advantage set forth as desirable in the statement of the object of the invention, and while I 105 have illustrated and described the preferred embodiment of the same, it is to be understood that I reserve the right to make such changes in the detail construction and arrangement of the parts as properly fall 110 within the spirit and scope of the appended claims.

I claim:—

1. In an acetylene gas generator, a carbide magazine suitably supported and provided with yieldingly-closed discharge-controlling means, and a cover having an opening, a door controlling the opening in the cover and provided with a slot in its free edge, a reserve carbide holder within the magazine below the said cover opening, and provided with a bottom discharge opening, a valve for closing said holder discharge opening, a latch pivoted to and within the holder and extending upwardly through the cover opening and the slot of the door for such opening, and provided at its upper end with a laterally-projecting arm and at its lower end with a hook normally engaging the said valve to hold it closed, and a gas 130

bell fitted over the magazine and adapted when sufficiently depressed, to open the yieldingly - closed discharge - controlling means, and a lug depending from the bell, 5 and adapted when the latter is properly turned and fully lowered, to engage the laterally-projecting arm of the latch to free the said valve to opening movement.

2. In an acetylene gas generator, a carbide magazine suitably supported and provided with yieldingly-closed discharge-controlling means, and a cover having an opening, a door controlling the opening in the cover and provided with a slot in its free 15 edge, a reserve carbide holder within the magazine below the said cover opening, and provided with a bottom discharge opening, a valve for closing said holder discharge opening, a latch pivoted to and within the holder and extending upwardly through the cover 20 opening and the slot of the door for such opening, and provided at its upper end with a laterally-projecting arm and at its lower end with a hook normally engaging the said valve to hold it closed, and a gas bell fitted 25 over the magazine and adapted when sufficiently depressed, to open the yieldingly-closed discharge-controlling means, a lug depending from the bell, and adapted when the latter is properly turned and fully lowered, 30 to engage the laterally-projecting arm of the latch to free the said valve to opening movement, and an inverted V-shaped retarder underlying the said valve controlled openings. 35

In testimony whereof, I hereunto affix my signature.

DOLPH MAUPIN.
